CALL RECORDING SYSTEM

Louis M. Potts, deceased, late of Evanston, Ill.,
by Martha W. C. Potts, executrix, Evanston,
Ill., assignor to Teletype Corporation, Chicago,
Ill., a corporation of Delaware

Application December 28, 1945, Serial No. 637,650

13 Claims. (Cl. 179—5.5)

1

The present invention relates to telephone systems and more particularly to call recording apparatus and circuits for use therein.

Apparatus and circuits have previously been devised for use in call recording or recording a calling subscriber's number at a called subscriber's station when the latter is absent and/or fails to answer the telephone. However, such solutions utilize very complicated apparatus in order to achieve the desired results.

Accordingly, the main object of this invention is to provide simplified apparatus and circuits for generating and recording a calling subscriber's number at an absent called subscriber's station.

A further object of the invention is to provide such apparatus and circuits which will operate automatically after a predetermined number of bell rings have gone unanswered.

Still another object of the invention is the provision of a special operator's station to which may be transmitted a message to be left at the absent called subscriber's station and which will be transmitted and recorded thereat under the control of the "leave word" operator.

A still further object of the invention includes apparatus whereby the calling subscriber's number will not be recorded at the absent called subscriber's station until the former concludes his attempted call and replaces his phone to a normal unoperated condition.

The features and advantages of the invention will become apparent from the following detailed description of specific embodiments thereof, when read in conjunction with the accompanying drawings, in which:

Figs. 1, 2, and 3 illustrate a telephone system incorporating therein call recording apparatus and circuits, and should be viewed together from left to right, respectively;

Fig. 4 is a view similar to Fig. 1 but incorporating apparatus whereby the call recording will not occur until the calling subscriber has replaced his station apparatus to an unoperated condition, and should be viewed with Figs. 2 and 3, and

Fig. 5 shows a "leave word" operator's station.

The following description will only refer to so much of the telephone system as is necessary for a complete understanding of the invention. The telephone system utilized is of the panel dial type, is standard, and is well known to those versed in the art.

Referring to Figs. 1 to 3, inclusive, Fig. 1 shows a calling subscriber's station A and lines 11 connected through a line finder district 12 to an office

selector 13, which is connected through an incoming selector circuit 14, Fig. 2, a final selector 16, Figs. 2 and 3, and over the lines 17 to a called subscriber's station B. The line finder and selectors are of the panel type and may be similar to the construction and operation of the switches disclosed in United States Patent 1,123,696, issued to Craft et al. on January 5, 1915.

In the following description an assumption 10 will be made that the calling subscriber's station A has been dialed in accordance with the call numbers of the called subscriber's station B and that the line finder district 12, the office selector 13, the incoming selector circuit 14 and the final 15 selector 16 have operated in accordance with the usual panel dial telephone circuit operation to connect the calling station A with the called station B and condition a talking circuit which will be established by the subscriber at station B 20 removing the receiver.

Such a connecting circuit may be traced over the lines 11 from the calling subscriber's station A to tip and ring connections 18 and 19, respectively. Further, the circuit may be traced from 25 grounded battery 21, through the left-hand winding of a repeater coil 22, through the winding of a relay 23 and over conductor 24 to the ring connection 19 and thus to one side of line 11. The completed circuit may be further traced from 30 the other side of line 11, through the tip connection 18, over a conductor 26, and through the left-hand winding of a repeater coil 27 to ground at 28.

Further tracing of the circuit, through the line 35 finder district 12 may be made from the induced current in the right-hand winding of the repeater coil 27, through sequence switch cam 29 which will form a closed path at this time, over a conductor 31 to a connector 32 in the office selector 13. The other half or side of the circuit may be 40 traced from the right-hand winding of repeater coil 22, over a conductor 33, through the sequence switch cam 34 which forms a closed path at this time and over conductor 36 to connector 37 in the office selector 13.

The upper half of the circuit from connector 32 45 in the office selector 13 may be traced to the incoming selector circuit 14 over conductor 38, through sequence switch cam 39 which forms a closed path at this time, through the left-hand winding of a repeater coil 41, over a conductor 42, through an armature 43 of a relay 44 which is in its unoperated or left-hand position, and through a conductor 46 and the left-hand winding 50 of a relay 47 to grounded battery 48. The opposite

side of the circuit may be traced from the connector 37 in the office selector, over conductor 49 to the incoming selector circuit 14, through the sequence switch cam 51 which will be in position to form a closed path at this time, over conductor 52, through the left-hand winding of a repeater coil 53, over a conductor 54, over a conductor 56, and through the right-hand winding of the relay 47 to ground at 57.

The circuit from the incoming selector circuit 14 to the final selector 16 will result through induced circuit occurring in the right-hand windings of the repeater coils 41 and 53. Such circuit may be traced from ground, through the right-hand winding of repeater coil 41, through 15 a sequence switch cam 58 which forms a closed path at this time, over a conductor 59, through an armature 61 of a relay 62 which is in its unoperated condition at this time, and over a conductor 63 to a connector 64 associated with the final selector circuit 16. The opposite half or side of the circuit may be traced from grounded battery 66, through the right-hand winding of the repeater coil 53, over a conductor 67, through the winding of a relay 68, through a sequence 20 switch cam 69 which will be closed at this time, over a conductor 71, through an armature 72 of the relay 62 which is in its downward or unoperated condition, and over a conductor 73 to a connector 74 associated with the final selector 16. The connectors 64 and 74 are connected by means of the lines 17 to the called subscriber's station B.

The circuit just described is conditioned only, and will be fully established upon the called subscriber answering his phone. The relay 23 at the line finder district 12 will be energized as the calling subscriber at station A has his receiver removed, but the relay 68 in the incoming selector 14 will not be energized as the receiver at station B has not been removed.

Upon the conditioning of the circuit described above a machine ringing relay 75 will be energized, in a manner well known in standard telephone practice, to cause the bell to ring at the called subscriber's station B indicating a telephone call. The relay 75 remains energized until such time as the called subscriber answers his phone, at which time superposed direct current prevents further operation. As a result of the energization of the relay 75 ringing current is applied through an alternating current relay 76 applied through an alternating current relay 76 which has been added. Even though the relay 75 remains energized the relay 76 will be caused to operate only intermittently, as the alternating current is supplied at intervals, interspersed by periods of rest. In the event that the subscriber at station B removes his receiver, causing relay 75 to become de-energized, as previously mentioned, the relay 76 will no longer receive alternating current and will remain de-energized.

However, in the event that no one is present at the called subscriber's station B or for some other reason the receiver is not removed from the hook, the telephone therat would continue to ring until such time as the calling subscriber A discontinued the call and the telephone circuit selecting apparatus automatically broke the circuit. In the present invention means are provided whereby in the event that there is no response at the called subscriber's station B after a predetermined number of bell rings, an apparatus will be operated to record the calling subscriber's number at the called subscriber's station. Such apparatus will now be described.

With reference to Fig. 1, a signal generating

apparatus 77 is provided which would be located at the central telephone station but which will generate numbers indicative of the subscriber's stations associated with such central station.

5 The signal generator 77 includes a pair of distributor rings such as the segmented ring 78 and the solid ring 79 which are traversed by the brushes 81. The segmented ring 78 is segmented in such a manner as to generate signals indicative of the station call letters of the calling station; that is, the identifying letters only. If in the following description it is assumed that the calling subscriber's number is BUC 6200 the ring 78 would be segmented in accordance with the letters BUC.

It might be well to point out at this time that the telegraph signals which are transmitted through the switching equipment are modulated alternating current of a suitable audible frequency. These signals are of this character so that they can be transmitted through condensers when required and are adapted to pass through the various link circuits commonly used in telephone service. The signals are later converted to direct current signals, as will be described, suitable for operating a monopulse printer of the type and in the manner disclosed and described in U. S. Patent No. 2,147,075, issued to W. J. Zenner on February 14, 1939. Such printer is by way of example only, as signals for operating permutation or other types of printers may be generated in a similar manner. According to the embodiment shown, wherein the printer disclosed in the Zenner patent is contemplated, the pattern of segmentation of ring 78 is such that each interval represented by the numeric 100 is equal to an isochronous code signal interval as shown in Fig. 1 of said Zenner patent.

The signal generator 77 is further provided with two sets of rings such as the segmented ring 82, solid ring 83, and segmented ring 84 traversed by the brushes 86 and the segmented ring 87, the solid ring 88 and the segmented ring 89 traversed by the brushes 91. The segmented ring 82 is segmented in such a manner as to transmit telegraph signals indicative of the thousands and hundreds components of the telephone number, such as 6 and 2 in the instant example. Likewise, the segmented ring 87 is segmented in such a manner as to transmit the tens and units components of the number, such as 00 in the instant example.

It will be understood that it is necessary to provide one-hundred each of the rings 82 and 87 in order that complete numbers from 00 to 99 may be transmitted in accordance with each telephone subscriber. However, in view of the fact that it would be mere repetition to include such a multiplicity of distributors in the instant drawings and would serve no useful purpose, one only of each of such rings have been illustrated. Only one station call letter distributor 78 need be included.

The generated signals, caused by the brushes 65 traversing their respective rings, originate with an alternating current generator 92 and pass over a common conductor 93 to a conductor 94 leading to the segmented ring 78, a conductor 96 leading to the segmented ring 82, and a conductor 97 leading to the segmented ring 87.

The segmented ring 78 is provided with a start segment 98 which must be of a length appreciably longer than the time required for a complete monopulse signal to be transmitted, insulated 75 segments 99 and signalling segments 101 which

are indicative, in monopulse code, of the letters BUC, as previously mentioned. The code segments 101 are insulated from each other and from the start segment 98 by means of the insulated segments 99. The brushes 81, 86, and 91 are continuously traversing their associated rings and thus a circuit may be traced from alternating current generator 92, over the common conductor 93, over the conductor 94, through the start segment 98, over brush 81 as it traverses the start segment, through the solid distributor ring 79 and over a conductor 102. The further circuit from conductor 102 may be traced through sequence switch cam 103 which forms a closed path upon the completion of the telephone circuit, over a conductor 104 having a condenser therein, through an armature 106 associated with a relay 107 but which is in its unoperated or leftward position, and over a conductor 108 to the conductor 24 previously described, which forms part of the ring circuit. As the brush 81 further traverses the segmented ring 78 it will pass over the code segments 101 and cause signals to be impressed on the conductor 24, over the circuit just described.

As previously mentioned, the segmented ring 82 was provided with code segments indicative of the thousands and hundreds components of the calling subscriber's number which are indicated by the numeral 109 and which are separated by means of insulation 111.

Also as previously described, segmented ring 87 generates signals indicative of the tens and units components, such segments being indicated by the numeral 112 and separated by the insulation 113.

It should be noted that the segments on the distributor rings 78, 82, and 87 are so positioned that none of them occur at the same time. Thus, as the brushes 81, 86, and 91 traverse their respective rings, the start signal would be transmitted first, then the station call letters (BUC), and finally the call numbers (6200) in such a manner that they would fall in their normal order.

At the same time that the circuit is completed between the two stations and the bell ringing occurs, a relay 114 is energized in accordance with standard telephone practice. Upon the energization of the relay 114 its armatures 116, 117, and 118 are attracted thereto, armatures 116 and 118 serving to disconnect the line relay 119 from the calling circuit, in a manner well known in telephone practice. The attraction of armature 117 will cause it to engage its associated electrical contact 121.

It might be noted that the relay 114 is comprised of three windings, the center winding causing the energization of the relay and the attraction of the armatures, whereas the purpose of the right-hand and left-hand windings will become apparent during the following description.

The attraction of the armature 117 in engagement with the contact 121 closes electrical circuits for the transmission of the numerals of the calling subscriber's station in a manner which will now be described.

As the brush 86 traverses the segmented ring 82 and particularly the code segments 109, an electrical circuit is completed which may be traced from the alternating current generator 92, over the common conductor 93, over the conductor 98 to the segments 109, over the traversing brush 86, through the solid distributor ring 33, over a cable or trunk 122, through resistor 123, through the winding of the right-hand coil of the

relay 114, over a conductor 124 to contact point 121, through the armature 117 attracted thereto, through a resistor and over a cable or trunk 126, through the solid ring 88, over the traversing brush 91, through the uninsulated segment 127 of the segmented ring 89, and over a conductor 128 to ground 129. As may be seen by reference to the segmented ring 89 the uninsulated portion 127 thereof is in alignment with the section of the segmented ring 82 assigned to the thousands and hundreds components of the calling subscriber's number, inasmuch as all the brushes rotate together.

It should be noted that there will be one hundred leads 96, one for each pair of digits 00 to 99, to represent thousands and hundreds. It is also to be noted that there will be one-hundred leads 126 which carry signals similar to those on leads 96 except that they represent tens and units. Apparatus is so provided that the signals will be generated in proper time relation to each other, so that while the thousands and hundreds signals are generated the leads 126 will be grounded, and vice versa. By this arrangement the two-hundred leads serve to give separate number indications to ten thousand different numbered telephone lines.

As the brushes further traverse their respective rings a circuit may be traced from alternating current generator 92, over the common conductor 93, over the conductor 97, through the code segments 112 of the segmented ring 87, over the traversing brush 91, over the solid ring 88, over the cable or trunk 126 and the resistor therein, through the armature 117 in engagement with contact 121, over the conductor 124, through the right-hand winding of the relay 114, through the resistor 123, over the cable or trunk 122, through the solid ring 88, over the traversing brush 86, through the uninsulated segment 131 of the segmented distributor ring 84, and over a conductor 132 to ground 129. In the present instance the uninsulated portion 131 of the segmented ring 84 is aligned with the portion of the segmented ring 87 assigned to the tens and units components of the calling subscriber's number.

The right-hand and left-hand windings of the relay 114 are so constructed that energization of the right-hand winding, due to the code segments being traversed as just described, will cause a similar energization or alternating current to be induced in the left-hand winding thereof. As a result of such occurrence the induced signals in the left-hand winding are transmitted over conductor 133 leading from the left-hand coil to the sleeve terminal 134, over a conductor 140, through the sequence switch cam 103 forming a closed path, over the conductor 104, through the armature 106, over the conductor 108, and will thus be reimpressed on the telephone circuit on the conductor 24 of the tip circuit.

Therefore, as the brushes 81, 86, and 91 traverse their associated segments, which occurs continuously, alternating current signals will be impressed on the conductor 24 in a manner as has just been described for both call letters and numerals indicative of the calling subscriber's station. However, even though this occurs during the time that the bell ringing mechanism is operating, the added superimposed alternating current will not affect the standard telephone circuit in any way.

It might be noted at this time that in the event that a called subscriber answered his phone

a relay 135 would energize according to standard telephone practice resulting in its armature 136 being attracted thereto and thus completing a circuit which may be traced from ground, through the armature 136 which is now in its attracted or right-hand position, over a conductor 137 to junction point 138, over a conductor 139, and through the winding of the relay 107 to grounded battery 141. The resultant energization of the relay 107, causing its armature 106 to be attracted thereto, would break the circuit previously traced from the conductors 102 and 140 and preclude further signals (BUC 6200) from being transmitted to the conductor 24. Therefore, under this condition no further signals indicative of the calling subscriber's station would be transmitted to or be placed on the telephone circuit, thus allowing conversation to occur in its normal uninterrupted manner.

As was previously mentioned, the bell ringing mechanism causes the relay 76 to operate, thus causing it to be energized and de-energized successively in accordance with the necessary rings of the bell. As a result of the energization of the relay 76 it will cause its associated armature 142 to be attracted thereto which results in an electrical circuit being established which may be traced from grounded battery 143, through the armature 142 to a contact point 144 with which it is now in engagement, over a conductor 146 and through the winding of a magnet 147, over a conductor 148 to junction point 149, over a conductor 151, through a sequence switch cam 152 which now forms a closed path condition, over a conductor 153 and through an armature 154 of relay 68, previously mentioned, to ground. As was also previously mentioned, inasmuch as the telephone circuit which was fully traced is not actually established until such time as the receiver is removed at the called station B, the relay 68 which forms part of the telephone path will not be energized and thus its armature 154 will be in an unoperated condition so as to allow the establishment of the circuit just traced. The magnet 147 will be energized and de-energized intermittently in accordance with a similar condition of the ringing relay 76.

The armature of the magnet 147 is formed of a lever 156 pivoted at 157 and normally urged in a clockwise direction by means of a spring 158. The lever 156 has pivotally connected thereto at 159 a pawl 161 which is normally urged in a counterclockwise direction by means of a spring 162 toward engagement with an associated ratchet 163. Counterclockwise motion of the pawl 161 is limited by means of a stop 164. The ratchet 163 is provided with a stop arm 166 associated therewith which is limited in its clockwise movement under urging of a coiled spring (not shown) by means of a stop 167 to return the ratchet 163 to its unoperated position.

Also associated with the ratchet 163 is a detent 168 which is pivotally mounted and which has an extended portion 169 which forms the armature of a magnet 171. The detent 168 is normally urged in a clockwise direction away from the ratchet 163 by means of a spring 172. However, during the time that the relay 68 is de-energized and the sequence switch cam 152 completes its circuit, an electrical circuit may be traced from ground, through the armature 154, through the conductor 153, through the sequence switch cam 152, over the conductor 151 to junction point 149, over a conductor 173, and

through the winding of the magnet 171 to grounded battery 174. The magnet 171 will thus become energized attracting its armature 169 thereto which results in the detent 168 being engaged in the teeth on the periphery of the ratchet 163 thereby preventing the ratchet from moving in a clockwise direction.

Each time that the armature 142 is attracted by the energization of the ringing relay 76, it engages contact 144 which results in the energization of the magnet 147. At such time the armature lever 156 will be attracted thereto, the pawl 161 will be moved upwardly in engagement with a tooth of the ratchet 163 and the ratchet will be turned in a counterclockwise direction a distance equal to the distance between successive teeth. The ratchet thus will be turned one tooth's distance each time the telephone bell rings at the called subscriber's station B.

As the ratchet 163 moves in a counterclockwise direction a predetermined distance, its stop arm 166 moving therewith will engage a movable swinger 176 causing it to pivot in a clockwise direction and engage its associated contact 177. At such occurrence, an electrical circuit is established which may be traced from grounded battery 178, through the contact 177, through the movable swinger 176, over a conductor 179, through a contact 181, through a movable swinger forming part of a common member 182 which is in engagement therewith at this time, over a conductor 183 to junction point 184, over a conductor 186 and through the winding of a relay 187 to ground. As a result of the completion of such electrical circuit the relay 187 will be energized and will remain in this condition inasmuch as the detent 168 will cause the electrical swing 176 to remain in contact with its associated contact point 177 through its action on the ratchet 163 until such time as the magnet 171 may become de-energized. Such magnet however does not become de-energized until such time as either the relay 68 becomes energized or the sequence switch cam 152 opens a circuit, which will not occur until the called subscriber removes his receiver from the hook or the calling subscriber abandons the phone call, respectively.

Upon energization of the relay 187 and the resultant attraction of its armatures 188 and 189 thereto, two electrical circuits are established, which will now be traced. One such electrical circuit may be traced from ground, over a conductor 191, through the armature 188, over a conductor 192, and through the winding of a magnet 193 to grounded battery 194. The resultant energization of the magnet 193 causes its armature 196 which is pivotally mounted at 197 and normally urged in a clockwise direction by means of a spring 198 to be moved in a counterclockwise direction thereby causing its detent arm 199 to engage the teeth of an associated ratchet 201 which is securely mounted to a shaft 202. The shaft 202 has a stop arm 203 securely fastened thereto which limits the clockwise movement of the shaft and ratchet by engagement with a stop 204 toward which it is biased by means of a coil spring, not shown.

The second electrical circuit which is established upon the energization of the relay 187 may be traced similarly to that with respect to the energizing circuit for the relay 187 up to the conductor 186, thence to contact 206, through the armature 189 in engagement therewith, over a conductor 207 to junction point 208, over a conductor 209 to an armature 211 of a relay 212 which

is at this time in a de-energized condition, through a contact 213, over conductor 214, and through the winding of the relay 212 to ground. As it was just mentioned that the circuit just established was traced through the armature 211 and depended on its being in its unattracted condition due to the de-energization of the relay 212, the energization of the relay 212 will cause such circuit to be broken momentarily, thus once again causing de-energization of the relay 212. The relay 212 acts as a stepping relay for a sequence switch or finder which comprises six contact rings 216 to 221, inclusive. The sequence switch or finder is provided so that one contact point on each of the rings 217 and 218 will be associated with the instant incoming selector circuit 14 and cause the alternating signals generated therein to be passed to an amplifier 223 in a manner and for a purpose which will be described hereinafter.

At such time as the stepping relay 212 advances the contact arms of the selector switch to a position whereby they engage the contact points associated with the instant example, which as may be seen on Fig. 3 is the third contact point, the circuit previously traced for the energization of the relay 187 over the conductor 183 to junction point 184 may be further traced over a conductor 224 to the third contact point of the selector ring 216, over the movable contact arm in engagement therewith, over a conductor 225 and through the right-hand winding of a relay 227 to ground. Upon the energization of the right-hand winding of the relay 227, the associated armature 228 will be attracted thereto placing it in engagement with contact 229 and extending the circuit from the conductor 226 through the contact 229, over the armature 228, over a conductor 231, through the left-hand winding of the relay 227, over a conductor 232, over the conductor 214, and through the winding of the stepping relay 212 to ground. Such acts as a locking circuit for the relay 212 and thus prevents the stepping switch from operating to move the movable arms past the No. 3 contact point of the contact rings 216 to 221, inclusive.

The relay 227 remains energized over its energizing circuit which was traced through the third contact point of the contact ring 216 and attracts its armatures 233 and 234 thereto, placing them in engagement with their associated contact points.

Due to the attraction of armature 233 a circuit is established which may be traced from the line 38 in the incoming selector circuit 14, over a conductor 236, through the third contact point of the contact ring 217, over the movable arm in engagement therewith, over a conductor 237, through the armature 233 and to the amplifier 223. Due to the attraction of the armature 234 a circuit may be traced from line 49 of the incoming selector circuit 14, over a conductor 238 to the third contact point of the contact ring 218, through the movable arm in engagement therewith, over a conductor 239, and through the armature 234 to the amplifier 223.

The amplifier 223 serves not only to amplify the alternating current signals transmitted from the signaling generator 77 but also to convert them from alternating current to direct current signals.

If the above circuit connections occur at the time of the transmission of any signal from the signal generator 77 other than that of the start signal 98, it will have no immediate effect on the apparatus hereinafter to be described. Thus,

in the following description it should be assumed that the circuits previously traced have been set up and that the brush 81 is traversing the start segment 98 and sending an alternating carrier current indicative thereof to the amplifier 223, which is thereat converted to direct current.

The reception and conversion to the direct current signal of the start impulse results in the establishment of a circuit which may be traced 10 from the amplifier 223, over a conductor 241, through the winding of a fast operating relay 242, through the winding of a slow operating relay 243 and over a conductor 244 back to the amplifier 223. The reason previously stated that 15 no effect would result from the transmission of any other than the start signal at this time is due to the fact that the slow to operate relay 243 is responsive only to the start signal of every one of the transmitted signals and will not 20 energize upon the reception of any other signals.

Upon the reception of the start signal and the energization of the relays 242 and 243 their armatures 247 and 246, respectively, will be attracted thereto. Due to the energization of the 25 relay 243 and the attraction of a second armature 248, an electrical circuit is established which may be traced from ground, through the armature 248, over a conductor 249, and through the winding of a relay 251 to grounded battery 252.

30 The resulting energization of the relay 251 causes its armature 253 to be attracted thereto resulting in the establishment of an electrical circuit from ground, over a conductor 254, through the attracted armature 253, over a conductor 256, and through the winding of a magnet 257 to grounded battery 258. The magnet 257 upon energizing attracts its armature 259, which is normally held away therefrom by means of a spring 261, causing it to pivot about its pivot point 262 and cause its detent portion 263 to engage a tooth in the ratchet wheel 201, previously described, thereby causing the ratchet wheel to be stepped a distance equal to the distance between successive teeth in a counterclockwise direction. As was also previously mentioned, the detent 199 is in engagement with the teeth of the ratchet wheel 201 thus precluding the ratchet from moving back to its original position after the magnet 257 becomes de-energized.

50 The movement of the ratchet 201 causes its shaft 202 to move a similar distance resulting in a cam 264 which is securely fastened to the shaft 202 to move a similar distance. Such movement of the cam 264 causes the high portion of 55 the periphery thereof to engage a movable swinger 266 and move it in a clockwise direction in engagement with an associated contact 267. Upon the closure of the contact pair formed by the swinger 266 and the contact point 267, an electrical circuit is established which may be traced 60 from ground, through the contact point 267, over the swinger 266, over a conductor 268, through contact point 269, over a movable swinger formed as part of the common member 182, over a conductor 271, and through the winding of a relay 272 to grounded battery 273.

The energization of the relay 272 causes its associated armatures 274, 276, and 277 to be attracted thereto resulting in the establishment 70 of certain circuits.

One of the just mentioned circuits may be traced from ground, through the armature 274, over a conductor 278, through the movable arm and third contact point of the contact ring 219, 75 over a conductor 279 and through the winding of

relay 62 (Fig. 2) to grounded battery 281. The relay 62 will become energized and cause its armatures 61 and 72 to be attracted thereto, thereby opening the conditioned circuit which was previously traced from conductor 59 to conductor 63 through armature 61, and from conductor 71 to conductor 73, through armature 72. Such formed part of the telephone circuit.

The attraction of the armatures 276 and 277 results in the establishment of an electrical circuit which may be traced from alternating current generator 282, through a conductor 283, over the armature 276, over a conductor 284, through the right-hand winding of a transformer 286, over a conductor 281, through the left-hand winding of a transformer 288, over a conductor 289, through the armature 271 and back to the alternating current source 282. As a result of the circuit just traced alternating current will be induced in the right-hand winding of the transformer 288, will pass over the conductor 291, through the movable arm and third contact point of the selector contact ring 220, over a conductor 292, through the armature 72, over the conductor 73, through the connector 74, over the lowermost of the two lines 17 shown in the final selector 16, over a conductor 293, through a contact pair 294 at the called subscriber's station B, over a conductor 296, through the right-hand winding of a printer magnet 297, through a condenser 298, and through an alternating current motor 299 utilized for driving the receiving monopulse printer.

The alternating current induced in the left-hand winding of the transformer 286 may be traced over a conductor 301, through the movable arm and third contact point of the selector contact ring 221, over a conductor 302, through the armature 61 which is associated with the relay 62 (Fig. 2), over the conductor 63, through the connector 64, leading to the final selector 16, over the uppermost of the two lines 17 to the called subscriber's station B, over a conductor 303, through a contact pair 304, over a conductor 306, through the left-hand winding of the relay 297, and through the condenser 298 to the motor 299. Inasmuch as the alternating current passes through the two windings of the magnet 297 in reverse directions no magnetic effect is produced but there is added a slight resistance to the current flowing to the motor 299. Such slight resistance merely diminishes slightly the alternating current supplied to the motor 299 but will not affect its operation due to the alternating current being supplied. However, direct current passes through the two windings in such a manner so that the magnetic effects are added, causing the magnet 297 to respond to the direct current. It should be further noted that even though the direct current is interrupted during signalling the alternating current is interrupted in one coil only and the motor 299 will continue to operate. A similar operation may be seen by reference to U. S. Patent No. 2,237,951, issued to L. M. Potts on April 8, 1941.

The reason for applying alternating current to the motor 299 at this time is to allow it to start into operation and come to an operating speed prior to the time that the printer is operated to record the code signals transmitted thereto.

While the transformers 286 and 288 have been shown as separate transformers such has been done for facility of illustration and actually the primaries are wound on a single magnetic core and the secondaries are also wound on the same

magnetic core. The two secondaries are wound in such a manner that they both deliver the same phase alternating current. However, when direct current passes through the two series connected windings they cancel each other and produce no magnetic effect, but merely act as resistors.

At the time of energization of the relay 62, an electrical circuit is established which may be traced from grounded battery 307 (Fig. 3), over a conductor 308, through a contact pair 309 which is closed at this time, over a conductor 311, through the right-hand winding of the transformer 288, over the conductor 291 and swinger arm to the No. 3 contact point of the 15 contact ring 220, over the conductor 292, through the armature 72 in engagement therewith, over conductor 73, through the connector 74 leading to the lowermost of the two lines 17 in the final selector 16, over the conductor 293, through the 20 contact pair 294, over the conductor 296, through the right-hand winding of the printer magnet 297, over a joining conductor 312, through the left-hand winding of the printer magnet 297, over the conductor 306, through the contact pair 25 304 (now closed), over the conductor 303 to the uppermost of the two lines 17, through the connector 64 leading to the incoming selector circuit 14, over the conductor 63, through the armature 61, over the conductor 302, through the 30 third contact point and swinger arm in engagement therewith of the contact ring 221, over the conductor 301 and through the left-hand winding of the transformer 286 to ground. The direct current just traced causes the printer magnet to 35 remain energized and precludes the operation of the printer until such time as a signal is received which releases the printer for operation in accordance with the description in the above-identified Zenner patent. The direct current so generated has no effect on the driving motor 299 inasmuch as because of the condenser 298 it does not pass to such motor; the condenser 298 passes alternating current only.

Upon the energization of the slow operating 40 relay 243 and fast operating relay 242, and subsequent attraction of the armatures 246 and 247, respectively, an electrical circuit is established which may be traced from ground, over a conductor 313, through the armature 246, over a conductor 314, through the armature 247, over a conductor 316, and through the winding of a relay 317 to grounded battery 318. The energization of the relay 317 causes its armature 319 to be attracted thereto resulting in engagement with the contact point 321 and the breaking of the contact pair 322. However, the energization and the resultant attraction of the armature has no effect at this time.

As the signal generator 17 (Fig. 1) completes the transmission of the start signal and the brush 81 passes to the first insulated portion 99 of the segmented ring 78, a signal will no longer be incoming to the amplifier 223 which results 60 in the de-energization of the fast operating relay 242 and the slow operating relay 243. Immediately, due to the dropping off of the armature 248, the relay 251 will de-energize causing its armature 253 to also fall away therefrom, 65 in turn resulting in the de-energization of the stepping magnet 257. The magnet 257 no longer attracts its armature 259 thereby allowing the pawl 263 to return to its normally unoperated condition away from the ratchet 201. Due to 70 the operation of the detent 199 prior to this time, 75

as previously mentioned, the ratchet 201 will remain in the stepped position.

The fact that the armatures 246 and 247 are no longer attracted by their respective relays results in ground no longer being supplied through both of these armatures to the relay 317 but instead substitutes ground over the conductor 313 and through contact 323 with which the armature 247 is now in engagement. Even through the relay 317 will not de-energize during this short transfer of ground circuits still there is no effect on the remaining circuits due to its de-energization.

As the brush 81 traverses further the segmented ring 78 causing the signal pulses 101 to be transmitted over the line and to the amplifier 228, such signals will result in the fast operating relay 242 becoming energized but will have no effect on the slow to operate relay 243 which, as previously mentioned, becomes energized only upon the receipt of the start signal due to its duration.

The energization of the fast operating relay 243 causes its armature 247 to be attracted thereto resulting in ground previously traced through contact 323 no longer being supplied to the circuit for the operation of relay 317 and inasmuch as relay 243 is not energized with its armature 246 attracted thereto, no ground will at this time be supplied for the relay circuit. However, even though the relay 317 becomes de-energized and its armature 319 falls away therefrom allowing the contact pair 322 to once again close, still there will be no effect on the remainder of the circuit at this time.

The receipt by the amplifier 223 of the signals generated as the brush 86 traverses the segmented ring 82 and as the brush 91 traverses the segmented ring 87 will have no effect on the signaling circuit other than that just described upon the receipt of the signals from segmented ring 78.

It is to be remembered that mention was made that the brushes 81, 86, and 91 continuously operate to traverse their respective rings. Therefore, after the cycle is completed, which was described immediately above, the brush 81 will once again traverse the start segment 98 of the segmented ring 78 resulting in the long duration start signal being transmitted over the line and received by the amplifier 223. Upon the receipt and conversion to direct current of such signal the fast operating relay 242 and the slow to operate relay 243 will once again be energized over the circuit which was previously fully described. As a result of the energization of the relay 243 its armature 248 is attracted thereto once again establishing the electrical circuit for the energization of the relay 251 which thereupon causes its armature 253 to be attracted thereto. The attraction of the armature 253 once again establishes the circuit for the energization of the magnet 257 causing its armature 259 to be attracted thereto and the pawl 263 to once again engage the ratchet wheel 201 and turn it in a counterclockwise direction a distance equal to the distance between successive teeth, in which position it is held by the detent 199 which is still in engagement with the teeth of the ratchet. Upon such movement of the ratchet 201 its shaft 202, to which it is securely fastened, likewise turns a similar amount thereby causing the cam 264 to likewise move in a counterclockwise direction causing its high portion to engage a movable swinger 324 and cause it to engage the associated contact 326.

Upon relays 242 and 243 becoming energized

and attracting their armatures 247 and 246, respectively, a circuit is once again established for placing ground in the circuit of the relay 317 thereby allowing such relay to energize and attract its armature 319 thereto. Such attraction results in the contact 321 being closed and the contact pair 322 becoming opened.

Upon the counterclockwise stepping of the cam 264 and the resultant movement of the swinger 324 into engagement with the contact 326, an electrical circuit is established which may be traced from ground, over the swinger 324, through the contact 326, through a contact 327, through a movable swinger forming part of the common member 102, over a conductor 328, and through the winding of a relay 329 to grounded battery 331. The energization of the relay 329 causes its armature 332 to be attracted thereto placing it in engagement with its associated contact 333 and causing the opening of the contact pair 309. The result of such occurrence is that battery 307 no longer will be supplied over conductor 308 and through contact pair 309 for supplying direct current to the printer magnet 297 but instead grounded battery 307 will be supplied through armature 319, contact 321, over a conductor 334, through armature 332, through contact 333, and over the line 311, as previously described, thereby causing the printer magnet 297 to remain energized.

As the brush 81 of the signal generator 77 passes from the start segment 98 to the insulated segment 99, the fast operating relay 242 and the slow operating relay 243 will once again become de-energized, thereby resulting in the armatures 247 and 246, respectively, no longer being held attracted and falling away therefrom. The only effect, with respect to the signal circuit is that ground for the energization of the relay 317 no longer may be traced through both of the armatures 247 and 246 but instead will now be traced through the contact 323 and the armature 247. At this time also the armature 248 will no longer be attracted resulting in the breaking of the circuit for the energization of the relay 251 which causes its armature 253 to also fall away. This in turn results in the circuit for the energization of the stepping magnet 257 being broken with the pawl 263 returning to its normal position out of engagement with the teeth of the ratchet 201. However, because detent 199 remains in engagement with the teeth of the ratchet, the ratchet will remain in its stepped position.

As the brush 81 of the signal generator 77 passes to the first signal segment 101 of the segmented ring 78 which is indicative of the first calling station letter (B) such will be transmitted to the amplifier 223, whereat it is converted to direct current, resulting in the fast operating relay 242 becoming energized. Inasmuch as, as was previously stated, the slow operating relay 243 does not become energized upon the receipt of any signal other than the start signal, it will not become energized at this time. The resultant attraction of the armature 247 of the relay 242 will remove ground supplied for relay 317, over conductor 313 and through contact 323 and as armature 246 is not attracted (relay 243 not energized) ground no longer will be supplied for the establishment and subsequent energization of the relay 317, thus reresulting in that relay becoming de-energized and its armature 319 falling away therefrom.

The fact that armature 319 is no longer in engagement with contact point 321 precludes

battery 307 from supplying direct current to the printer magnet 297 inasmuch as contacts 321 and 309 are both open at this time, thus allowing the printer to start operating in accordance with the signal interval, in a manner described fully in the Zenner patent.

Upon the brush 81 passing from the segment 101 indicative of the letter B to the subsequent insulated segment 99, no signal impulse will be received by the amplifier 223 and the relay 242 will become de-energized. Such results in the armature 247 falling away and ground once again being supplied over conductor 313 and through contact 323 and armature 247 for the circuit of relay 317 thereby causing that relay to energize. Upon such occurring the armature 319 becomes attracted, engages its contact 321, and battery 307 is once again supplied over the previously traced circuit thereby resulting in the energization of the printer magnet 297. Such results in the letter B being recorded by the monopulse printer.

The apparatus will thereafter function in a similar manner in order that the letters "UC" and the numerals 6200 may be transmitted and recorded by the printer at the called subscriber's station B. It should be remembered that during all this time, that is, as the brush 81 completes its passage over its signal segments and as the brushes 86 and 91 traverse their signal segments all of which will be recorded in accordance with the monopulse code at the receiving printer, that the slow to operate relay 243 will not become energized.

After the brushes have made a complete cycle or traversal of their associated rings, the brush 81 will once again traverse the start segment 98 causing the start signal to be transmitted over the line to the amplifier 223 wherein it will be converted to direct current. Such signal causes the fast operating relay 242 to become energized and also causes slow to operate relay 243 to become energized, causing the armatures 247, 246, and 248 to be attracted.

The attraction of armature 248 results in a circuit once again being established for the energization of the relay 251 attracting its armature 253 thereto. The attraction of the armature 253 establishes the circuit once again for the energization of the stepping magnet 257 thereby attracting its armature 259 and causing the pawl 263 to step the ratchet 201 another step. Such movement of the ratchet causes the shaft 202 to likewise move resulting in the cam 264 being moved a third step in a counterclockwise direction. The effect of such stepping of the cam at this time is to cause its high portion to move member 182 in an upward direction resulting in the movable swingers connected thereto being moved away from engagement with the contacts 181, 269, and 327, thereby causing certain circuits to be broken, as will now be described.

The opening of the circuit at contact 327 results in the de-energization of the relay 329 thereby removing the armature 332 from engagement with the contact 333 and allowing the contact pair 309 once again to close. The disestablishment of such circuit allows grounded battery 307 to be applied directly to the printer magnet 297, over the conductor 308, through the contact pair 309, and over a circuit which was previously described.

The opening of the circuit at contact 269 removes ground which was previously supplied for the energization of the relay 272 and thereby re-

sults in the de-energization of such relay causing its armatures 274, 276, and 277 to fall away from their associated contacts. As a result of armature 274 no longer engaging its associated contact 5 the circuit previously traced for the energization of the relay 62 (Fig. 2) no longer will be established and such relay will become de-energized, its armatures 61 and 72 no longer being attracted thereto. The result of these armatures no longer 10 being attracted to their relay serves to disconnect the selector contact rings 220 and 221 from the lines 17 leading to the called subscriber's station B, thus breaking the circuit previously described for the direct current to the printer magnet 297, but instead completes connecting lines 17 in the telephone circuit initially described.

The relay 272 being de-energized results in the armatures 276 and 277 no longer being attracted and serves to remove the alternating current source 282 from the transformers 286 and 287 as previously explained. Even though such did not occur the alternating current previously described as being supplied to the printer motor 299 causing it to operate would no longer perform such function due to the fact that the armatures 61 and 72, over which the circuit for such alternating current was traced, no longer are in a position to connect to the lines 17 in such a manner as has just been described.

As a result of the circuit being broken at contact 181 the battery which was supplied for the relays 187, 212, and 227 no longer will be supplied and these relays will all become de-energized. As a result of the de-energization of the relay 227, 20 its armatures 233 and 234 will no longer be attracted and the circuit will be broken for supplying 25 the signals generated by the signal generator 17 to the amplifier 223.

Upon the de-energization of the relay 187 its 40 armature 188 will no longer be attracted thereto and because of this will break the circuit which had been traced for the energization of the magnet 193. The de-energization of such magnet will 45 result in its armature 196 no longer being attracted thereto and under the influence of the spring 198 being biased in a clockwise direction in which position the detent portion 199 is no longer in engagement with the teeth of the ratchet wheel 201. Under this condition the ratchet wheel 201 50 will return through spring power, which is not shown, in a clockwise direction to an unoperated position whereat its stop arm 203 engages the limiting stop 204.

As the ratchet 201 and connected shaft 202 55 move in a clockwise direction, the cam 264 will move similarly. Such movement to the cam 264 returns it to its normal unoperated position, whereat its high portion will no longer be presented to the swingers 266 and 324 and the member 182. The latter elements will thus return to 60 the condition initially described.

Thus, it may be seen that after a complete signal has been received and recorded at the called 65 subscriber's station B which is indicative of the calling subscriber's number, the apparatus will automatically preclude itself from further operation. Under this condition the bell ringing mechanism will continue to operate until such time as the subscriber at the calling station A returns his receiver to the hook thereby causing the telephone apparatus to relinquish all the selecting circuits under the control of the selector control relay in a manner which is well known in the telephone art.

75 It might be mentioned at this time with respect

to the prior description wherein it was stated that after a predetermined number of bell rings that the ratchet wheel 163 would be advanced sufficiently to cause the movable swinger 176 to engage its associated contact 177, that such predetermined number of rings should be picked in order to allow a person sufficient time to reach his telephone but not to allow too much time to elapse. In the event that the latter were true, called subscribers may refuse to answer their telephone until such time as the calling subscriber's number had been recorded at the called subscriber's station and thus if the called subscriber felt like conversing with the particular person whose number had been recorded he would remove his receiver. Under this latter condition too much equipment would be necessary and too much time expended in the use thereof in order for it to be a worth while service.

Referring back to Fig. 1 and the calling subscriber's station A, after the calling subscriber has assumed that there is no one at the called station and decides to abandon the telephone call, he returns his receiver to the hook, which, as previously described, is well known in the telephone art and which causes the relinquishment of the seized circuits. Also, as is well known in the telephone art, this results in the cut-off relay 114 becoming de-energized thereby resulting in the breaking of the circuits from the signaling generator 77 to the telegraph circuits previously transmitting the number 6200. At this time the selector cam 103 will also be positioned in such a manner that no circuit may be established therethrough and the remaining circuit from the signal generator 77 will be disconnected from the telephone lines. Thus, at this time the signal generator 77 no longer will supply alternating current carrier signals to the telephone lines but instead will continue to operate having no effect in the circuits. However, at such time as another call is instituted from the calling station A the signal generator 77 will once again be connected in the line circuits in a manner which has previously been described.

In the event that it is desired to completely preclude the possibility of a called subscriber refusing to answer his telephone until such time as the calling subscriber's number has been recorded thereat, apparatus has been provided in a modification of the invention to overcome such contingency. Such modification is shown in Fig. 4.

In view of the fact that in main the apparatus of Fig. 4 is similar to that of Fig. 1 and operates in a similar manner, like reference numerals are utilized in Fig. 4 wherever possible and will indicate members similar to those shown and described with respect to Fig. 1.

Referring specifically to Fig. 4, an assumption should be made that the calling subscriber at station A has removed his receiver and has dialed the number of the desired called subscriber's station B. The apparatus will operate in a manner similar to that previously described in order to complete a telephone circuit which as previously mentioned was traced through the winding of the relay 23. Upon the energization of the relay 23 its armatures 336, 337, and 338 will be attracted thereto.

Due to the attraction of the armature 338 an electrical circuit is established which may be traced from ground, through armature 338, over a conductor 339, and through the winding of the slow to release relay 341 to grounded battery

342. The slow to release relay 341 will become energized attracting its armatures 343 and 344 thereto.

The attraction of the armature 336 serves to supply ground through the armature 336, over a conductor 346, and through a sequence switch cam 347, now closed, to energize the selector control relay (not shown) which operates to hold the seized circuits in accordance with standard telephony operation.

The signal generator 77 operates in a manner similar to that described with respect to Fig. 1 to generate signals indicative of the calling subscriber's number over the conductors 102 and 140, through the selector cam 103, over the conductor 104 and through the armature 106. The circuit may then be traced over a conductor 348, through a condenser therein, through the armature 343, over a conductor 349, through armature 337, and over a conductor 350. However, the circuit for impressing the generated signals over the circuit just described to the line 24 at the line finder district 12 will not be completed at this time because in order for such establishment it must be traced through the armature 337 which does not make contact with the conductor 349 due to its being held in its attracted position by the energization of the relay 23.

The bell ringing mechanism will operate similarly to that previously described, and the apparatus of Figs. 2 and 3 will also operate similarly with the exception that no subscriber's station identifying signals will be transmitted over the telephone circuit to cause recording at the called subscriber's station.

At such time as the calling subscriber at station A decides that the called subscriber at station B is not present and returns his receiver to the hook, the apparatus will function to cause the de-energization of the relay 23. Even though the armature 338 is no longer attracted to supply ground to the energizing circuit of the relay 341, this relay will not immediately de-energize inasmuch as, as was previously mentioned, it is a slow to release relay.

The armature 337 of the relay 23 will return to its unattracted position thus allowing the generated signals to pass in a manner similar to that described with respect to Fig. 1 to the conductor 104, through the armature 106, over the conductor 348, through the armature 343 which is in its attracted position, over the conductor 349, through the armature 337 now in its unattracted position, and over the conductor 350 to the line 24 from whence it will pass over telegraph circuits to the apparatus already described of Fig. 3.

The apparatus disclosed in Figs. 2 and 3 will function in a manner similar to that previously described in order that the generated signals which are transmitted over the telephone circuit may be recorded at the called subscriber's station B. The slow to release relay 341 will be so timed that it will not be de-energized until such time as a complete calling subscriber's signal has been recorded. At this time, however, the relay 341 de-energizes thereby allowing its armature 343 to return to its unattracted position thus breaking the circuit which was previously described as having been established for the conduction of signals generated by the signal generator 77 to the line 24 of the telephone circuit. Thus at this time the apparatus will once again be in readiness for the calling subscriber at station A to initiate another telephone call and to operate at that time.

It might be mentioned at this time that upon the replacing of the receiver to the hook at the calling subscriber's station even though relay 23 becomes de-energized immediately, the remaining circuit connections between the calling subscriber's station A and the called subscriber's station B will not be relinquished until such time as the called subscriber's number may be recorded at the called subscriber's station. Such occurs because the relay 341 is energized during this time, and its armature 344 is attracted thereto thus supplying ground over an obvious circuit through the sequence switch cam 347 for the selector control relay, not shown.

The above apparatus will operate to record a calling subscriber's number at the called subscriber's station but has no provisions wherein messages or other material may be transmitted and recorded at the called subscriber's station. In view of such, apparatus disclosed in Fig. 5 has been provided which contemplates the use of a "leave word" operator's position for receiving orally a message to be left at the called subscriber's station, the operator controlling transmission of such message.

Only sufficient apparatus has been provided in Fig. 5 in order to disclose the operation of this embodiment of the invention. It is contemplated that the apparatus for causing the bell ringing mechanism to operate and the apparatus operating to translate and record the signals at the called subscriber's station, such as shown in Figs. 2 and 3, will be incorporated for use with the present modification as will the regular panel dial system telephone circuits.

Specifically, referring to Fig. 5, a calling subscriber's station has been identified by the numeral 351 which is connected by means of lines 352 through a final selector 353 to the instant "leave word" operator's station. It might be noted that while only a final selector has been disclosed, it is to be understood that a line finder district, incoming selector, and any other necessary selectors may be included even though not shown. The calling subscriber's station 351 will be connected to the operator's "leave word" system through the various selectors including the final incoming selector 353 as a result of the calling subscriber dialing some number associated with the "leave word" operator, such as the numeral 0, for instance. As a result of such dialing, a circuit will be established which may be traced over line 352, over a conductor 354, through an armature 356, through the left-hand winding of a relay 357, to grounded battery 358. As a result of the energization of the relay 357 its armature 359 will be attracted thereto resulting in the grounded battery 358 being applied through the armature 359 and over a conductor 361 to the grounded illumination source 362, such as a normal light bulb. The illumination of such light will notify the "leave word" operator that somebody desires to communicate with her and she thereupon will insert the plug 363 in the jack 364. Such action results in grounded battery 366 being supplied through the plug and jack connection, through the winding of a relay 367 to ground, resulting in the energization of that relay and the attraction of its armature 368. Upon the armature 368 moving toward the relay it opens the circuit which was previously traced over conductor 354 and through the armature 356 for causing the illumination of the light 362, thereby resulting in the light being extinguished.

At the same time, the operator may throw the

key 368 to its upward position thereby causing the associated key contacts 369 to be removed from engagement with their inner contacts and placed in engagement with their outer contacts. 5 Such action causes the plug 363 to be connected over the plug leads, through the key contacts 369 and their outer associated contacts to an operator's set which is indicated generally by the numeral 371 and which is of the type in general 10 use at the present time. The "leave word" operator may thus communicate orally, utilizing the set 371, with the calling subscriber, thereby being advised of the message which the calling subscriber wishes delivered to the called subscriber.

After the operator has been advised as to the desired message the plug 363 will be removed from engagement with the jack 364 and inserted in the jack indicated generally by the numeral 372 instead. 20 The key 368 will be withdrawn from engagement with its contacts 369 and instead placed in a position to engage its associated contacts 373 in such a manner as to place them in engagement with their outer contact points instead of their 25 inner contact points. The result of such action is to establish a circuit including the dial unit 374, through the outer contacts associated with the key contacts 373, through these key contacts, over the conductors 376, through the key contacts 369 to the plug 363, thence to the jack 372 and over the telephone circuit. The operator thence will operate the dial 374 dialing the proper 30 number for the called subscriber's station which will operate through line finder district indicated 35 generally by the numeral 377, through the regular telephone sequence switches which are not shown, and eventually over lines 378 to the called subscriber's station 379. The effect of this will be to complete a telephone circuit between the 40 "leave word" operator's station and the called subscriber's station.

After such circuit has been established and the standard telephone bell ringing mechanism has operated in a manner well known in the art 45 and as indicated previously, the apparatus disclosed in Figs. 2 and 3 will operate in a manner as described with respect to the principal embodiment of the invention. Thereafter the operator will remove the key 368 from engagement 50 with its associated key contacts 373 allowing such key contacts to engage their inner contact points resulting in the dial unit 374 being disconnected from the circuit. Simultaneously a key will be operated to cause the key contacts 381 to engage 55 their associated contact points resulting in an alternating current generator 382 being connected over the conductors 383 to the primary of the transformer 384 which induces current in the secondary windings of the transformer 384 60 which current passes over the conductors 386 to the contact points associated with the key contacts 381 and thence over previously traced circuits including key contacts 373, the conductors 376, the key contacts 369, the plug 363 and the 65 jack 372. However, the alternating current from the source just described does not normally pass over the described circuits because of a shunt circuit between the conductors 386 which includes a conductor 387, a manually operable key contact pair 388, a contact pair 389 and a conductor 391. Thus, during a normal condition at which time the key contact pair 388 is closed as is the contact pair 389, a shunt will exist on the line 70 whereby no alternating current will be transmitted thereover.

The normally closed contact pair 389 is within a monopulse transmitter 392 which is of the type disclosed and described in U. S. Patent 2,173,147 issued to W. J. Zenner on September 19, 1939. Such patent discloses a similar contact which is likewise normally closed.

In order for the apparatus to be put into operation the operator must open the key contact pair 388 twice in succession, each time of a fairly long duration in order that the shunt may be removed from the line and alternating current impulses may be transmitted thereover which will cause the operation of the apparatus shown in Fig. 3 and particularly the double stepping of the ratchet 281 to advance the cam 264 to a position whereat the movable swingers 266 and 324 engage their associated contacts 267 and 326, respectively. As has been fully described hereinbefore, such results in the monopulse receiver at the called subscriber's station being conditioned in readiness for the receipt of monopulse signals and the recording of the proper message in response thereto.

Thereafter, the key 368 will be again closed resulting in the shunt once again being supplied to the circuit, thereby terminating the transmission of alternating current thereover. However, the "leave word" operator will now operate the monopulse transmitter 392 in a manner fully described in the just previously mentioned Zenner patent resulting in the contact pair 389 being opened in accordance with monopulse signals for the characters of the message to be transmitted which has the effect of once again removing the shunt from the circuit and allowing the alternating current to pass thereover in accordance with the monopulse signals. Such current will be received in the amplifier 223 and cause the operation after conversion to direct current of the relays and apparatus as disclosed and in a manner described with respect to the principal embodiment.

It should be remembered that though alternating current has been described as passing over the line, direct current will still be utilized for the telephone circuit connection as is normally done in the telephone field.

After the "leave word" operator has transmitted the entire message by means of operating the monopulse transmitter 392, the plug 363 may be removed from the jack 312 thereby resulting in the telephone circuits becoming disestablished and returning to their original unselected conditions. Of course, the key 388 may also be operated to send a long pulse, which will cause operation similar to that of the initial description.

While a single "leave word" operator's unit has been shown and described it should be noted that there may be several in each exchange which may also have several operators and apparatus for their use which would include a plurality of jacks 364 and lights 362 in order that more than one call could be handled at a single time at the "leave word" operator's station.

It is obvious that both the initially described apparatus and the "leave word" operator's apparatus may be utilized in the same system. Thus, the latter apparatus would only be utilized when it is desired to leave a message other than the mere calling subscriber's designation.

It should also be noted that the manual operable key 388 which has been provided for the transmission of two long impulses may be substituted by a button operated commutator or by any other means which will serve the purpose.

Even though specific embodiments of the invention have been described it is fundamental that such invention is not limited to the specific disclosures shown, but instead includes any modifications or alterations which incorporate the spirit of the invention.

What is claimed is:

1. In combination with a telephone circuit including a central station, a calling subscriber's station, a called subscriber's station, and bell ringing mechanism, of means at said central station to generate repeatedly a group of signals indicative of the calling subscriber's station, means to impress the repeated group of generated signals on said telephone circuit when said circuit is in a ringing position, a telegraph recorder at said called subscriber's station, means to condition said telegraph recorder for operation, means to cause one only of said repeated group of generated signals indicative of said calling subscriber's station to be recorded by said telegraph recorder, and means to cause said conditioning means to operate after a predetermined period of operation of said bell ringing mechanism.
2. In combination with a telephone circuit including a central station, a calling subscriber's station, a called subscriber's station, and bell ringing mechanism, of means at said central station to generate repeatedly a group of signals indicative of the calling subscriber's station, means to impress the repeated group of generated signals on said telephone circuit when said circuit is in a ringing position, a telegraph recorder at said called subscriber's station, means to condition said telegraph recorder for operation, means to cause a group of generated signals indicative of said calling subscriber's station to be recorded by said telegraph recorder, means to preclude the recording of more than a single group of said repeatedly generated group of signals indicative of said calling subscriber's station, and means to cause said conditioning means to operate after a predetermined period of operation of said bell ringing mechanism.
3. In a communication system, a telephone circuit including a central station, a calling subscriber's station, a called subscriber's station and bell ringing mechanism, means under the control of the calling subscriber's station to place said circuit in a ringing position and cause operation of said bell ringing mechanism, means at said central station to generate repeatedly a group of signals indicative of the calling subscriber's station, a telegraph recorder at said called subscriber's station, means to condition said telegraph recorder for operation, means to cause said conditioning means to operate after a predetermined period of operation of said bell ringing mechanism, means operating after said ringing position is discontinued to cause said repeated group of generated signals to be impressed on said circuit, and means to cause one only of said repeated group of signals indicative of said calling subscriber's station to be recorded on said telegraph recorder.
4. In a communication system, a telephone circuit including a central station, a calling subscriber's station, a called subscriber's station and bell ringing mechanism, means under the control of the calling subscriber's station to place said circuit in a ringing position, and cause operation of said bell ringing mechanism, means at said central station to generate repeatedly a group of signals indicative of the calling subscriber's sta-

tion, a telegraph recorder at said called subscriber's station, means to condition said telegraph recorder for operation, means to cause said conditioning means to operate after a predetermined period of operation of said bell ringing mechanism, means operating after said ringing position is discontinued to cause said repeated group of generated signals to be impressed on said circuit, means operating in response to the repeated group of signals indicative of said calling subscriber's station to further condition said telegraph recorder for operation, and means responsive to a succeeding one of said repeated group of signals indicative of the calling subscriber's station to cause the operation of said telegraph recorder.

5. In a communication system, a calling station, a called station, a central station, bell ringing mechanism, means at said central station to generate repeatedly a group of signals indicative of the calling station, means to connect said calling station and said called station through said central station for communication, a recorder at said called station, means to condition said recorder for operation, means to transmit said repeated group of code signals indicative of said calling station, means to cause said recorder to respond to one only of said repeatedly transmitted group of signals, and means to cause said conditioning means to operate after a predetermined period of operation of said bell ringing mechanism.

6. In a combined telephone-telegraph circuit, a calling subscriber's station, a called subscriber's station, means to condition a circuit between said calling and called subscriber's stations, means to generate alternating current signals on said circuit indicative of said calling subscriber's station, a telegraph recorder at said called subscriber's station, means to convert said alternating current signals to direct current signals, means responsive to the failure of a talking circuit to be established and under the control of said direct current signals to condition said printer for operation, and means to cause said printer to record signals indicative of said calling subscriber's station.

7. In a call recording system, a calling subscriber's station, a called subscriber's station, a central station, bell ringing mechanism, means to condition a circuit between said calling and called subscriber's stations through said central station, means at said central station to generate on said circuit repeatedly a group of signals indicative of said calling subscriber's station, a recorder at said called subscriber's station, means to condition said recorder for operation, means to cause said conditioning means to operate after a predetermined period of operation of said bell ringing mechanism, means responsive to certain of said repeated group of signals to further condition said recorder for operation, and means to cause the succeeding repeated group of signals to be recorded by said recorder.

8. In a call recorder system, a calling subscriber's station, a called subscriber's station, a central station, bell ringing mechanism, means to condition a circuit between said calling and called subscriber's stations through said central station, means at said central station to generate repeatedly a group of signals indicative of said calling subscriber's station, each of said repeated group of signals including an initial start impulse, a recorder at said called subscriber's station, means to condition said recorder for oper-

ation, means to cause said conditioning means to operate after a predetermined period of operation of said bell ringing mechanism, means under the control of said start impulses to further condition said recorder for operation, means under the control of said start impulses to cause said recorder to record one of said repeated group of signals indicative of said calling subscriber's station, and means under the control of said succeeding start impulse to preclude further operation of said recorder.

9. In combination with a telephone circuit including a calling subscriber's station, a called subscriber's station, and means to establish a circuit between said stations including tip, ring, and sleeve connections, of means to generate signals indicative of the calling subscriber's station, means to cause some of said signals to be impressed on said sleeve connection, means to cause the remaining of said signals to be impressed on said ring connection, and means to cause all of said signals to be transmitted to said called subscriber's station.

10. In a call recording system, a calling subscriber's station, a called subscriber's station, means to transmit a plurality of similar groups of signals indicative of said calling subscriber's station, means to precede each group of signals by a special signal longer than the longest signal in each group, a recorder at said called subscriber's station, and means controlled by said special signal to render said recorder responsive to a single group of signals only.

11. In a communication system, a calling station, a called station, switching apparatus, means to extend a circuit between said stations through said switching apparatus, means to generate groups of signals indicative of said calling subscriber's station, means responsive to a disconnect signal from said calling station to impress said groups of signals on said circuit, means to prevent said switching apparatus from becoming released, and means to record a single group of signals at said called station.

12. In a communication system, a calling station, a called station, switching apparatus, means to extend a circuit between said stations through said switching apparatus, means to generate groups of signals indicative of said calling subscriber's station, means responsive to a disconnect signal from said calling station to impress said groups of signals on said circuit, means to prevent said switching apparatus from becoming released, means to record a single group of signals at said called station, and means to release said switching mechanism to disconnect said circuit after said single group of signals is recorded.

13. In a call recording system, a calling subscriber's station, a called subscriber's station, a central station, bell ringing mechanism, means to condition a circuit between said calling and called subscriber's stations through said central station, means at said central station to generate

65 on said circuit repeatedly a group of signals indicative of said calling subscriber's station, a recorder at said called subscriber's station, means to condition said recorder for operation, means to cause said conditioning means to operate after a predetermined period of operation of said bell ringing mechanism, means responsive to certain of said repeated group of signals to further condition said recorder for operation, means to cause the succeeding repeated group of signals to be recorded by said recorder, and means under the

control of the next succeeding repeated group of signals to preclude further operation of said recorder.

MARTHA W. C. POTTS,
Executrix Under the Last Will and Testament of 5
Louis M. Potts, Deceased.
